(57) **CLAIM**

The ornamental design for an audio assembly, as shown and described.

DESCRIPTION

FIG. 1 is a front perspective view of an audio assembly according to a first embodiment of our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof;

FIG. 7 is a bottom elevation view thereof;

FIG. 8 is a front perspective view of an audio assembly according to a second embodiment of our design;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top elevation view thereof; and,

FIG. 14 is a bottom elevation view thereof.

Broken lines are environmental only and form no part of the claimed design.

The portions shown in a pattern of stipple illustrate areas of contrasting appearance.
